UNITED STATES PATENT OFFICE.

MINNIE O. DENTON, OF ARMUCHEE, GEORGIA.

DISH-WASHING MACHINE.

1,123,995.

Specification of Letters Patent.

Patented Jan. 5, 1915.

Application filed May 6, 1914. Serial No. 336,781.

To all whom it may concern:

Be it known that I, MINNIE O. DENTON, a citizen of the United States of America, residing at Armuchee, in the county of Floyd and State of Georgia, have invented certain new and useful Improvements in Dish-Washing Machines, of which the following is a specification.

This invention relates to dish washing machines and it has for its object the provision of an improved article of this nature so arranged that the dishes may be conveniently adjusted and placed in position upon a supporting stand or rack, outside of the dish washing machine proper, or in other words, while said rack is resting upon a table. After which, the rack with the dishes may be placed in the machine and a current of boiling water forced therethrough to thoroughly cleanse the dishes. Means are provided for then draining the water from the receptacle and permitting the highly heated dishes to dry.

A very important feature of the invention is the construction of the dish supporting rack. This rack is so constructed as to hold the dishes in the most advantageous position for their ready and thorough cleansing. Furthermore, means are provided for clamping the dishes to hold them against accidental movement to thereby prevent breakage during the time that they are being washed. The construction of this stand further renders it possible to place the cups, saucers, and plates in such position with relation to each other that they will all be thoroughly subjected to the action of the water set in motion by the agitator, said dishes being held in a slanting, overlapping position around the agitator.

Further objects and advantages of the invention will be set forth in the detailed description which now follows.

In the accompanying drawing, Figure 1 is a vertical sectional view of the outer receptacle of the washing machine, illustrating the dish supporting rack and clamp in elevation. Fig. 2 is a plan view of the machine. Fig. 3 is a sectional perspective view of a part or the central rack. Fig. 4 is a plan view of said rack, with the agitator therein. Fig. 5 is an enlarged partial plan view and, Fig. 6 is a detail view of the twisted wires hereinafter described, and Fig. 7 is a plan view of the clamp.

Like numerals designate corresponding

parts in all of the figures of the drawing.

Referring to the drawing the numeral 5 designates a receptacle or can which may be of any convenient size or shape. While this can may be made of any desired material, I preferably form it of sheet metal such as galvanized iron, and provide it with a copper bottom so that it may be placed upon an oil, or other stove, for the purpose of heating the water contained therein. This can is provided with a removable cover 6 preferably of the push in type, carrying a casting 7 having bearings 8 and 9 for the reception of a rotative shaft 10. This shaft is provided with an operating crank or handle 11 by which rotation may be imparted through said shaft to a gear wheel 12. This gear wheel is adapted to mesh with a bevel pinion 13 that is fast upon a vertical shaft 14. The shaft 14 passes through a sleeve 15 that is supported from the cover 6. Above the cover 6 the sleeve 15 is spun out to form a collar 17 which not only adds rigidity to the parts but forms a bearing surface for the lower face of the pinion 13.

A fan or agitator blade 18 having the reversely curved edges 18^a is secured upon the lower end of the shaft 14 whereby endwise movement of the shaft is prevented. In other words, the securing of the fan upon the lower end of the shaft prevents upward movement of the shaft and the pinion bearing against the collar 17 prevents downward movement of said shaft.

It is apparent that movement of the crank 11 will impart rotation to the shaft 14 through the connections described and will consequently rotate the fan or agitator blade 18. The receptacle 5 is provided with a drain cock or faucet 19 by which the water may be drained from the receptacle as will be hereinafter set forth.

A very important feature of my invention is the dish supporting rack shown in Figs. 3, 4, and 5. This rack comprises the central frusto conical wire rack, made up of the vertical frame wires 20 and the spiral wire 21 woven back and forth into engagement with the vertical frame wires.

The detailed construction of this rack is of the utmost importance because it is by virtue of the construction of this rack that I am enabled to support the dishes in the most advantageous position to subject them to the action of the water set up by the agitator.

As is clearly illustrated in Fig. 3, the frame wires 20 are bent upon themselves at 22, to form inside feet, and are then bent outwardly to lie in a slanting position at 24, are bent to horizontal position at 25, are then bent upon themselves at 26 to form outside feet and are continued inwardly and upwardly at 27 to form braces, the ends of which are attached to the central frusto conical member. The horizontal wires 28 which may be continuations of the spiral wire 21 are woven back and forth to form the floor comprising the horizontal portion 29 and the inclined portion 30. Wires 31 15 and 32 are twisted into engagement with each other and with the wires 20 and form means for supporting the knives, forks, spoons, and the like as illustrated in Fig. 6. A guard rail is formed by the hoop 36 provided with catches or hooks 37 adapted to engage any of the links of chains 38. The ends of these chains are secured to the edges of a clamp 39. This clamp is preferably formed of a single and continuous wire bent 25 to spiral formation. Its function is to clamp the pile of dishes firmly into engagement with the rack to thereby prevent their breakage either during the time that they are being placed in position or during the 30 time that they are being washed. The handles 40 are engaged with the hoop 36 and are turned inwardly at their upper end to form handle portions 41 which lie close to the top of the frusto conical member in 35 such position that the hand and wrist of the operator will not strike the edges of the can when the rack is being placed in position in said can.

The operation of the device is as follows: 40 With the cover and agitator removed from the can 5, and with the rack likewise removed from the can, the dishes are arranged in the most advantageous position upon said rack, the cups rest upon the slanting 45 portion 30 of the wall of the rack and are consequently held in position to be thoroughly washed and at the same time they lie in such a slanting position that they will readily drain. It is of course, understood 50 that the cups are arranged in position with their open sides toward the agitator. Upon the horizontal portion 29 of the floor of the rack, are arranged the saucers and plates, the saucers being placed directly behind the 55 cups with their lower edges resting upon the horizontal portion of the floor and with their upper edges leaning against the central frusto conical portion of the rack. Behind the saucers, the plates are placed and 60 as many additional dishes as desired are arranged about the central frusto conical member, as is illustrated in dotted lines in Fig. 1. The dishes so arranged, are held in position by the clamp 39, this clamp being 65 held in position by the chains 38. Since

any of the links of these chains may be engaged with the catches 37 it follows that a vertical adjustment of the clamp may be had to thereby clamp in position a large or small quantity of dishes. When the dishes 70 have been placed in position and clamped upon the rack, the rack is lifted into the can 5 and then the top 6 is placed in position, the agitator passing downwardly through the central cone shaped portion of the rack. It is apparent therefore, that if rotation be 75 imparted to handle 11 rotation will likewise be imparted to the agitator 18, and this will force a current of water, and preferably very hot or boiling water, through 80 the dishes, very thoroughly cleansing the same.

After the dishes have been sufficiently washed the faucet 19 is opened and the water is drained from receptacle 5. The 85 feet 27 hold the lowermost dishes a sufficient distance above the bottom of the receptacle 5 to prevent the adherence to said dishes of any of the food products washed from the dishes above. The cover 6 is then 90 removed and the air is permitted to circulate freely through the receptacle 5. Since the dishes are in a highly heated condition from the effects of the boiling water, they will rapidly dry themselves. The structure 95 herein shown and described provides for very effectively and thoroughly washing dishes and the advantageous result secured is largely due to the fact that the structure of the supporting rack is such that the 100 dishes are arranged in the best possible manner to permit the water to thoroughly act upon them.

A place is provided for every article, preferably I provide places for twelve cups, 105 twelve saucers, twelve plates, etc., though of course, the number may be varied at will. While the drying of the dishes may be accomplished by merely draining the water from the can, it is apparent that the same 110 object may be accomplished by lifting the rack from the can. Furthermore, since the body of the can is free of any of the attachments the can may be used for many other purposes than as part of the dish-washer. To this end I may provide if desired, a separate cover adapted to take the 115 place of the cover 7.

While the elements shown and described are well adapted to serve the purposes for 120 which they are intended, it is to be understood that the invention is not limited to the precise construction set forth, but includes within its purview such changes as may be made within the scope of the ap- 125 pended claims.

Having described my invention, what I claim is:

1. In a device of the character described the combination with a receptacle and an 130

- agitator therein of a removable dish supporting rack extending around said agitator through the top of which said agitator is adapted to pass, said rack comprising a 5 pan-like base member, a clamp vertically movable with relation to said rack and extending around the upper portion of said rack and arranged to hold dishes in engagement with the outer face of said rack and 10 fastening devices extending between said pan-like member and said clamp.
2. In a device of the character described, the combination with a receptacle adapted to contain water, an agitator therein, a 15 movable cover by which said agitator is carried and a rack comprising a central frusto conical member of wire and a pan like member surrounding the base of said frusto conical member, and a frusto conical 20 clamp adapted to embrace the first named frusto conical member and means for securing said clamp against movement with relation to said frusto conical member.
3. In a device of the character described, 25 the combination with a receptacle adapted to contain water, of an agitator therein, means for imparting rotation to said agitator and a dish rack comprising a central frusto conical member made up of frame 30 wires and a spiral wire, reversely twisted wires for the reception of knives and forks, a pan like structure about the base of said frusto conical member, cup holding brace 35 wires spanning said pan like member and a frusto conical clamp of wire embracing the first named frusto conical member together with means for holding said clamp against movement.
4. A rack of the character described comprising a plurality of vertical frame wires 40 bent back upon themselves to form legs, a plurality of horizontal wires bent into engagement with said first named wires forming a horizontal floor portion and an inclined 45 floor portion, said inclined floor portion lying at the juncture of said horizontal floor portion and the body portion of the rack.
5. A rack of the character described comprising a central cylindrical member and a 50 pan like member surrounding said cylindrical member, said pan like member comprising a horizontal floor portion and an inclined floor portion lying at the base of said cylindrical member.
- 55 6. A rack of the character described comprising a central cylindrical member formed of a plurality of vertical frame wires bent upon themselves at their lower ends to form 60 legs, then bent upwardly and outwardly to form inclined portions, then bent to form a horizontal portion, then bent upon themselves to form outer legs, then bent inwardly and upwardly to form brace wires, in combination with horizontal wires woven into engagement with the inclined and horizontal portions of said frame wires, to form a floor.
7. A rack of the character described comprising a central cylindrical member formed of a plurality of vertical frame wires bent 70 upon themselves at their lower ends to form legs, then bent upwardly and outwardly to form inclined portions, then bent to form a horizontal portion, then bent upon themselves to form outer legs, then bent inwardly 75 and upwardly to form brace wires, in combination with horizontal wires woven into engagement with the inclined and horizontal portions of said frame wires, to form a floor, and a railing surrounding said horizontal 80 floor portion.
8. A rack of the character described comprising a central cylindrical member formed of a plurality of vertical frame wires bent 85 upon themselves at their lower ends to form legs, then bent upwardly and outwardly to form inclined portions, then bent to form a horizontal portion, then bent upon themselves to form outer legs, then bent inwardly 90 and upwardly to form brace wires, in combination with horizontal wires woven into engagement with the inclined and horizontal portions of said frame wires, to form a floor, and a railing surrounding said horizontal 95 floor portion, a clamp adapted to fit over said central cylindrical portion and chains extending between said clamp and said railing.
9. A rack of the character described comprising a central cylindrical member formed of a plurality of vertical frame wires bent 100 upon themselves at their lower ends to form legs, then bent upwardly and outwardly to form inclined portions, then bent to form a horizontal portion, then bent upon themselves to form outer legs, then bent inwardly 105 and upwardly to form brace wires, in combination with horizontal portions of said frame wires, to form a floor, a railing surrounding said horizontal floor portion, a clamp adapted to fit over said central cylindrical portion 110 and chains extending between said clamp and said railing, and handles secured to a part of said railing.
- In testimony whereof I affix my signature in presence of two witnesses.

MINNIE O. DENTON.
